AUDION AMPLIFIER CIRCUIT

Application filed August 13, 1925. Serial No. 50,114

This invention relates to audion amplifier circuits and in particular to a circuit which is compensated for the flow of retroactive currents through the grid plate capacity of an audion tube. By this compensation we diminish or completely eliminate the effects upon the input circuit terminals due to the variations in potential across the output circuit load. In the copending application of 10 Stuart Ballantine, Serial No. 34,388, filed June 2, 1925, patented August 13, 1929, No. 1,724,819, there is described a Wheatstone bridge circuit whereby such compensation is produced. When this Wheatstone bridge is 15 substantially balanced to eliminate or reduce the flow of retroactive currents through the grid plate capacity of the audion tube, the circuit when used as an amplifying stage is approximately one-way in action. Moreover 20 this balance is substantially independent of frequency, and the circuit is admirably adapted for use in cascade amplification. We have discovered a circuit which while retaining all of these advantages, has the additional advantage that one of the terminals 25 of the input circuit may be connected directly to the audion filament. This cannot be done in the construction of an amplifier according to the Ballantine circuit, although 30 we are aware that in the Ballantine circuit, as well as in other well known circuits, an intermediate point of either the input or the output circuit may be brought to the filament potential. When the input circuit of 35 an amplifier stage comprises a tuned circuit containing an inductance and a tuning condenser, it is in many cases a structural disadvantage to have both sets of plates of this condenser permanently above the ground or 40 filament potential. Moreover when the Ballantine circuit is used in each stage of a cascaded amplifier, it is impossible to bring the tuning condensers of each stage to a common terminal, such as ground, or the common filament terminal of the several audions. 45 By our invention we have overcome this difficulty and have succeeded in grounding one terminal of the input circuit, or in the 50 case of a cascaded amplifier having tuned

input circuits, bringing all the condensers to a common terminal.

Referring now to the drawing, Fig. 1 shows a single amplifier stage arranged according to our invention. Fig. 2 is a diagrammatic representation of the essential alternating current elements of this circuit as they appear when represented in the form of a conventional bridge diagram. Fig. 3 is a cascaded amplifier arranged according to our invention.

In Fig. 1 the inherent grid-plate capacity of the tube is represented by the dotted lines at C_m . The inherent grid-filament capacity is similarly shown at C_g . Connected in parallel with C_g there may be an external capacity C_l between the grid and filament. This external capacity has been shown for the sake of generality, but its use may be unnecessary. The sum of C_g and C_l is what we term C_c . One input terminal of the stage is connected directly to the filament while the other input terminal is connected to the grid through a coil L_2 which is coupled to a coil L_3 in the plate circuit. Coil L_2 , therefore, is in series with the capacity C_c and the grid and filament of the tube. L_2 may be coupled to a part or all of L_3 but in practice a close coupling with the lower portion L_b of the coil L_3 is preferred.

This circuit arrangement will be seen to result in a Wheatstone bridge in which one arm is a capacity between grid and filament, another arm is a capacity between grid and plate, a third arm is the portion L_a of the coil L_3 , and the fourth arm comprises the portion L_b of coil L_3 , coil L_2 , and the mutual inductance M_{23} . The input of the audion stage is between the filament and a point G' which is at the opposite end of coil L_2 from that end 2, which is connected to the grid. The output of the stage is between the plate and filament. It is understood that our invention is not limited to any particular form of input and output circuits. We have, however, shown as a preferred form a tuned input circuit L_1C_2 , and a tuned output circuit L_4C_3 .

This arrangement of circuit elements and connections will be more clear in conjunction

with Fig. 2 which is a conventional bridge diagram of the essential alternating current elements of the circuit of Fig. 1.

In Fig. 3 two radio frequency stages of 5 amplification I and II, each connected according to our invention, are shown working into a detector stage III.

In all figures such standard elements as 10 filament batteries and rheostats, "B" battery by-pass condensers, and the like have been omitted for the sake of simplicity.

By partially or completely balancing the 15 Wheatstone bridge arrangement herein described a diminution or complete elimination of retroactive effects may be obtained. The conditions for balance of the bridge may be seen from Fig. 2 to be:

$$\frac{Cc}{Cm} = \frac{L3 - M23}{M23}$$

20 and this balance is theoretically independent of frequency. In actual practice we obtain a balance substantially independent of frequency over a considerable range. We have 25 found that the various circuit elements can be so designed and proportioned that the effects of distributed capacities in the coils and of other parasitic capacities in a physical structure are negligible over a substantial 30 range of frequencies.

The potentials of the various points in an 35 audion circuit are commonly measured with respect to the alternating current potential of the audion filament, which is usually at the lowest potential of the circuit and is commonly grounded. By the lower terminal of either the input or the output circuit we mean that terminal which has the lowest alternating 40 current voltage and hence approaches most nearly to the alternating current potential of the audion filament.

We claim:

45 1. In the process of arranging the impedance elements of an audion amplifier stage as a Wheatstone bridge network having the output circuit and the input circuit of the stage as the conjugate arms thereof, the step which comprises connecting one terminal of the said input circuit of the stage directly 50 to the filament of the audion.

55 2. The method of preventing retroaction from the output circuit to the input circuit of an audion amplifier stage having an audion with grid and cathode terminals, the elements of said stage being arranged as a Wheatstone bridge capable of being balanced at radio frequencies and including a balancing arm in series with the said input circuit between said grid and filament terminals, which comprises arranging said balancing 60 arm between the grid terminal of the audion and said input circuit.

65 3. An audion amplifier stage of the type having a resonant input circuit and an impedance network of the Wheatstone bridge

type and capable of being balanced to limit regeneration, said network including as adjacent balancing arms thereof a substantially pure capacity between the grid and filament of the audion, and an impedance between one terminal of the said resonant input circuit and the grid terminal of the audion. 70

4. An audion amplifier stage wherein an audion and a plurality of impedances form an alternating current Wheatstone bridge 75 network, characterized by the fact that capacity between grid and filament terminals of the audion and capacity between grid and plate terminals constitute adjacent balancing arms of the bridge, and a third balancing arm is connected between said grid and the input circuit of the stage. 80

5. An anti-regenerative audion amplifier stage of the type in which the impedance network is arranged in the form of a Wheatstone bridge circuit having as conjugate arms thereof the input and the output circuits of said stage, characterized by the fact that one input terminal of the amplifier stage is directly connected to the filament of the tube, 90 and that the other input terminal of the stage is connected to the grid of the tube through a coil in inductive relation with the output circuit of the tube. 95

6. A cascaded audion amplifier each stage 100 of which comprises an audion and a plurality of impedances arranged in the form of a Wheatstone bridge circuit having as the conjugate arms thereof the input and the output circuits of said stage and characterized by the fact that one input terminal of the amplifier stage is connected to the filament of the tube, and that the other input terminal of the stage is connected to the grid of the tube through a coil in inductive relation with the output circuit of the stage. 105

7. An audion amplifier stage the impedance network of which is arranged in the form of a Wheatstone bridge circuit, having as the conjugate arms thereof the input and the output circuits of said stage, said network comprising an input circuit having two terminals one of which is the filament of the audion tube, a capacity between the grid and filament of said tube, and an inductance connected in series between the grid of said tube and the remaining input terminal, said inductance being coupled to a coil in the plate circuit of said tube. 110

8. An audion amplifier stage the impedance network of which is arranged in the form of a Wheatstone bridge having as the conjugate arms thereof the input and the output circuits of said stage, and which comprises an input circuit having a terminal connected to the filament of the audion tube, a capacity between the grid and filament of said tube, an inductance between the plate and filament of said tube, and a second inductance between the grid of said tube and a 120 125 130

second terminal of said input circuit, said second inductance being coupled to said first mentioned inductance.

9. A signal receiving network comprising
5 a plate-filament circuit including an output
inductance and a source of direct current en-
ergy, an input element between the grid and
filament, and means for preventing retroac-
tion of the output voltage variations upon
10 the input element including a second induct-
ance inductively coupled to the output in-
ductance, said second inductance being elec-
trically connected between the grid and input
15 element, and an external condenser connected
between the grid and one of the other elec-
trodes, the capacity between grid and fila-
ment and between grid and plate being so pro-
portioned with respect to the degree of cou-
20 pling between the inductances that the net-
work acts as a balanced Wheatstone type
bridge wherein the terminals of the input ele-
ment are conjugate with respect to the out-
put circuit.

In testimony whereof, we affix our signa-
25 tures.
